Inventor

UNITED STATES PATENT OFFICE.

EDMOND B. STEARNS, OF TOWANDA, KANSAS.

CLOTHES-PIN.

SPECIFICATION forming part of Letters Patent No. 665,039, dated January 1, 1901.

Application filed May 29, 1900. Serial No. 18,439. (No model.)

To all whom it may concern:

Be it known that I, EDMOND B. STEARNS, a citizen of the United States, residing at Towanda, in the county of Butler and State of Kansas, have invented new and useful Improvements in Clothes-Pins, of which the following is a specification.

This invention relates to new and useful improvements in clothes-pins; and its primary object is to provide a device of simple and durable construction which is cheaply manufactured and whereby the clothes may be securely fastened to the line.

A further object is to provide a pin of this character which is adapted to be permanently connected to the clothes-line and which may be moved from one point to another upon the same.

To these ends the invention consists in the novel construction and combination of parts hereinafter more fully described and claimed, and illustrated in the accompanying drawings, showing the preferred form of my invention, and in which—

25 Figure 1 is a side elevation showing different positions of the pin upon a clothes-line. Fig. 2 is a detail view thereof.

Referring to said figures by numerals of reference, 1 are the similar members of the 30 pin, which are formed of two sections of wire twisted for a suitable distance from each end and said wires being separated and looped at a point equidistant from the ends, forming bails 2. The ends of the wires are firmly and 35 permanently clamped within a cap or clasp 3, as shown.

The pin is normally held in position upon the line, as shown at the right end of Fig. 1, and when it is desired to fasten the clothes 40 upon the line said pin is inverted, so as to

bring the contracted ends thereof upon the cloth. Bails 2 are then grasped by the hand and the pin drawn downwardly, and it is obvious that the sections 1 will form a wedge which will firmly clasp the clothes to the line. 45 When it is desired to remove the pin, the same is merely pressed upward, or if it is difficult to move the same in this manner the bails 2 are pressed together, causing the arms 1 to spread slightly apart, thereby permitting 50 the ready removal of the pin.

In the foregoing description I have shown the preferred form of my invention; but I do not limit myself thereto, as I am aware that modifications may be made therein without departing from the spirit or sacrificing the advantages thereof, and I therefore reserve the right to make such changes and alterations as fairly fall within the scope of my invention.

Having thus fully described my invention, what I claim as new, and desire to secure by Letters Patent, is—

1. A pin comprising oppositely-disposed similar members each formed of twisted wires, 65 oppositely-inclined bails formed by said wires between the members, and means for permanently securing the free ends of the members.

2. A clothes-pin comprising oppositely-disposed similar members each formed of twisted wires, a cap for permanently securing the free ends of the members together, and oppositely-inclined bails formed by said wires between the members.

In testimony whereof I affix my signature 75 in presence of two witnesses.

EDMOND B. STEARNS.
